BISECTOR

Edward E. Elwert, Galesburg, Ill., assignor to W. C. Dillon & Company, Inc., Chicago, Ill., a corporation of Illinois

Application June 30, 1941, Serial No. 400,393

6 Claims. (Cl. 33—64)

This invention relates in general to geometric instruments, and more particularly to an instrument for bisecting any desired angle.

In line construction, i. e., the erection of electric lines or wires and their supporting poles, one of the important problems to be solved is that of accurately locating the correct placement for anchors for pole guy wires. This work is normally done by a surveyor, since accuracy is essential in measuring for correct anchor hole location. Correctly locating an anchor for the guy wire for any particular pole is a case of ascertaining the direction of the resultant of the lines of force applied to that pole by the lines supported thereby, or of bisecting the angle between the lines of force to which the pole is subjected. Improper location of a guy wire anchor will result in shifting of position of the top of the pole slackening of the pole lead, and subsequent failure under storm conditions or at any time that the line wires are overtensioned. It has been authoritatively estimated that, where the proper sizes of pole, guy strand and anchor have been employed, 90% of all corner and other guyed pole failures is due to the anchor not having been located correctly.

A principal object of this invention, therefore, is to reduce to an absolute minimum the cost of wire and pole replacement and the interruption to service due to guyed pole failures, while eliminating the expense and consumption of time normally attendant with accurate placement of guy wire anchors.

Another important object of the invention is the provision of simplified means for accurately locating the correct position for anchors for pole guy wires without necessitating the use of any engineering or surveying skill in the operation thereof.

A further object of the invention is the provision, in a device for bisecting any desired angle, of means for so engaging a pole as to adapt the device for the particular purpose of bisecting the angle formed by the lines of force to which the pole is subjected.

Numerous other objects and advantages of the invention will be apparent as it is better understood from the following description, which, when taken in connection with the accompanying drawing, discloses a preferred embodiment thereof.

In the drawing:

Figure 1 is a top plan view of a device embodying the features of the invention;

Fig. 2 is a longitudinal section taken substantially on the line 2—2 of Fig. 1; and

Fig. 3 is a diagrammatic plan view illustrating the device in use.

Referring more particularly to the drawing, reference number 11 indicates in general a device embodying the features of the invention

which comprises a supporting member 12, a pair of sighting members 13, a slide member 14 and a pair of links 15. The forward end of the supporting member 12 is pointed, as indicated at 16, to enable the supporting member to be slightly embedded in a pole.

The sighting members 13 are disposed on opposite sides of the supporting member 12, and are pivotally connected therewith by means of a bolt 17. As noted in Fig. 2, washers 18 are interposed between each of the sighting members 13 and the supporting member 12. A nut 19, which may have its outer surface knurled if desired, is threaded on the bolt 17 and, together with the latter, is adapted to clamp or hold the sighting members 13 against movement relative to the supporting member 12 when tightened. The rear end of each sighting member 13 is pivotally connected to the forward end of an associated link 15 by a rivet 21. The rear end of each of the links 15 is in turn pivotally connected to the slide member 14 by means of a screw 22 having threaded engagement with a suitable tapped aperture in the slide. These apertures are provided in vertical alignment with each other in the top and bottom portions of the slide member 14.

In the normal condition of the device, the sighting members 13 are free to pivot upon the bolt 17. As will be appreciated from Fig. 1 of the drawing, if one of the sighting members 13 is held stationary, and the other sighting member is swung about their mutual pivot 17, the linkage and slide connection between the sighting members and the supporting member 12 will cause the latter to be moved correspondingly. Such resulting movement of the supporting member 12 will be caused by the link 15, which is associated with the sighting member that has been moved, moving the slide 14 longitudinally on the supporting member. Since the other sighting member is being held stationary, the resulting longitudinal movement of the slide 14 on the supporting member 12 will cause the latter to be swung a corresponding degree about the pivot 17. Whenever it is desired to retain the several parts of the device in any adjusted position, it is only necessary to tighten the nut 19. This results in a clamping together of the two sighting members and the supporting member 12.

Fig. 3 of the drawing illustrates diagrammatically the use of the instant devices for its intended purpose of properly locating the correct placement for the anchor for a pole guy wire. In this illustration, reference numeral 23 indicates a corner pole for which a guy wire is to be placed, and the line poles which form the angle with the corner pole 23 which it is desired to bisect are represented by reference numerals 24. The point 16 of the supporting member 12 is embedded slightly in the pole 23 by tapping on the

rear end of the supporting member. The rear end of the supporting member 12 is held in horizontal position by one of the linemen, or other operators of the device, the embedding of the point 16 being just enough to keep the same from dropping down. This operator, or the other one working with him, then adjusts one of the sighting devices into alignment with one of the poles 24, as indicated in Fig. 3 by the broken sighting lines 25. One operator holds this first sighting member 13 in such adjusted position, the other operator similarly aligns the other sighting member 13 with the other pole 24. As has been noted, such adjustment of the second sighting member 13 will result in the supporting member 12 being swung about the pivot 17. The operator maintaining the supporting member 12 in a horizontal position will, of course, permit such angular movement thereof. Such horizontal movement of the supporting member 12 resulting from the adjustment of the sighting members 13 is the reason for embedding the point 16 in the pole 23 only a sufficient distance to keep the same from dropping down.

The sighting members 13, having thus been aligned with the lines of sight to the poles 24, the several parts of the device may be locked in adjusted position by tightening of the screw 19. The supporting member 12 in its adjusted position then indicates the correct anchor hole location 26, which may be at any desired point on the center line of the supporting member 12, which is indicated by the broken line 27 in Fig. 3. In other words, regardless of what the particular angle may be that is formed by the lines of sight 25, after the device has been adjusted in the manner described, the center line 27 of the supporting member 12 will accurately bisect such angle to properly locate the correct placement for an anchor for the pole to be guyed.

It is thought that the invention and many of its attendant advantages will be understood from the foregoing description, and it will be apparent that various changes may be made in the form, construction and arrangement of the parts without departing from the spirit and scope of the invention or sacrificing all of its material advantages, the form hereinbefore described being merely a preferred embodiment thereof.

I claim:

1. A device for bisecting any angle having its vertex defined by a vertical pole, comprising a member engageable at one end with said pole, sighting means pivotally mounted on said member and movable respectively into alignment with the sides of the angle, and links pivotally connected to said sighting means and pivotally and slidably connected with said member to move the latter in response to such movements of the sighting means into alignment with the line bisecting said angle.

2. A device for locating the correct placement for guy wire anchors for line supporting poles, comprising a member having one end engageable with a pole, sighting means mounted adjacent one end of said member on the same vertical pivot and movable horizontally into alignment with the lines of force applied to the pole by the lines supported thereby, and links pivotally connected to said sighting means and pivotally and slidably connected with said member adjacent the other end thereof to automatically move the latter horizontally in response to such movements of said sighting means to point toward the correct placement for a pole guy wire anchor.

3. A device for locating the correct placement for guy wire anchors for line supporting poles, comprising a bar having the forward end thereof pointed for driven engagement with a pole, a pair of sighting members pivotally mounted on the same vertical pivot on said bar adjacent the forward end thereof, a link pivotally connected at one end to each of said sighting members and pivotally interconnected at their other ends and mounted for sliding movement on said bar adjacent the rear end thereof to automatically swing said bar horizontally about the forward end thereof in response to such movements of said sighting members to point toward the correct placement for a pole guy wire anchor, and adjustable means associated with said vertical pivot for clamping said sighting members to said bar to retain the same in any desired adjusted position.

4. A device of the class described, comprising a supporting bar, a pair of sighting members pivotally mounted intermediate their respective ends at the same point adjacent one end of said bar, a member mounted adjacent the other end of said bar for longitudinal sliding movement thereon, and a link pivotally interconnected between each of said sighting members and said slide member, with the pivotal connections between said links and said slide member being in alignment with each other.

5. A device for bisecting any desired angle, comprising an elongated member having an end positionable at the vertex of the angle, a sighting member pivotally mounted intermediate its ends on said elongated member and movable into alignment with one side of said angle, means interconnecting said elongated member and said sighting member and having a portion slidable along said elongated member in response to the aligning movement of said sighting member, another sighting member pivotally mounted intermediate its ends on said elongated member and movable into alignment with the other side of said angle, and means interconnecting said elongated member and said other sighting member and operable in response to the aligning movement of said other sighting member for aligning said elongated member with the bisector of said angle when said other sighting member is aligned with the said other side of said angle.

6. A device for bisecting any desired angle, comprising an elongated member having an end positionable at the vertex of the angle, a sighting member having a pivot intermediate its ends on said elongated member and movable into alignment with one side of said angle, means interconnecting said elongated member and said sighting member and having a portion slidable along said elongated member in response to the aligning movement of said sighting member, another sighting member secured intermediate its ends to the pivot of the first said sighting member on said elongated member and movable into alignment with the other side of said angle, means interconnecting said elongated member and said other sighting member and operable in response to the aligning movement of said other sighting member for aligning said elongated member with the bisector of said angle when said other sighting member is aligned with the said other side of said angle, and clamping means at said pivot for clamping said sighting members and said elongated member together releasably to retain them in any adjusted position.

EDWARD E. ELWERT.
